(57) **CLAIM**

The ornamental design for a fork, as shown and described.

DESCRIPTION

FIG. 1 is a perspective view of a fork showing my new design;

FIG. 2 is a side elevational view of thereof, the opposite side being a mirror image thereof; and,

FIG. 3 is a top plan view thereof, the bottom plan view being a mirror image thereof.

The broken line depiction of tine separation is for illustrative purposes only and forms no part of the claimed design.
